(57) **CLAIM**

The ornamental design for a swimming pool telescoping pole, as shown and described.

DESCRIPTION

FIG. 1 is a front perspective view of a first embodiment of a swimming pool telescoping pole showing my new design; FIG. 2 is a right side elevational view thereof; FIG. 3 is a left side elevational view thereof; FIG. 4 is a bottom view thereof; FIG. 5 is a top view thereof; FIG. 6 is a rear elevational view thereof; and, FIG. 7 is a front elevational view thereof.

The broken lines illustrate unclaimed portions of the swimming pool telescoping pole that form no part of the claimed design. A portion of the pole is shown with broken gaps to represent an indeterminate length. The indeterminate portion of the article forms no part of the claimed design.
